IRONING BOARD FOR PRESSING POINTS OF A GARMENT

Verner H. Lawton, P.O. Box 569, Myrtle Creek, Oreg.

Filed Mar. 27, 1961, Ser. No. 64,509

Term of patent 7 years

(Cl. D49—1)

Fig. 1

Fig. 2

Fig. 3

FIG. 1 is a side elevational view of an ironing board for pressing points of a garment, showing my new design; FIG. 2 is a top plan view thereof;

FIG. 3 is an elevational view thereof taken from the left end of FIG. 1.

The side not shown is the same as the side shown.

I claim:

The ornamental design for an ironing board for pressing points of a garment, as shown and described.
